CASING FOR A PHOTOGRAPHIC PROJECTOR

Harvey C. Bjornlie and Irving S. Korach, Los Angeles,
Calif., assignors to Douglas Aircraft Company, Inc.,
Santa Monica, Calif.

Filed Oct. 30, 1963, Ser. No. 77,213

Term of patent 14 years

(Cl. D61—1)

Fig. 1

Fig. 2

Fig. 3

Fig. 4

Fig. 5

FIGURE 1 is a front elevational view of a casing for a photographic projector embodying our new design;

FIGURE 2 is a side elevational view thereof, the side not shown being identical thereto in appearance;

FIGURE 3 is a rear elevational view thereof;

FIGURE 4 is a top plan view thereof; and

FIGURE 5 is a bottom plan view thereof.

We claim:

The ornamental design for a casing for a photographic projector, substantially as shown and described.
